UNITED STATES PATENT OFFICE.

WALTER C. BARNHART, OF SEATTLE, WASHINGTON.

GRINDING-MACHINE.

1,169,377.

Specification of Letters Patent. Patented Jan. 25, 1916.

Application filed March 8, 1915. Serial No. 13,048.

To all whom it may concern:

Be it known that I, WALTER C. BARNHART, a citizen of the United States, residing at Seattle, in the county of King and State of Washington, have invented certain new and useful Improvements in Grinding-Machines, of which the following is a specification.

This invention relates to improvements in grinding machines and, more particularly, 10 to a machine of this class which is adapted for facing the peripheral faces of pulleys or wheels.

The object of my improvements is to produce an extremely efficient and conveniently 15 operated pulley-grinding machine which will embody relatively few parts and which is capable of grinding a pulley without removing the same from its shaft and which will be frictionally operated through power 20 applied through the agency of such shaft.

The invention consists in certain parts and details and combinations of the same, as will be hereinafter described and claimed.

In the accompanying drawings, Figure 1 25 is a perspective view of a grinding machine embodying the present invention assembled and ready for use. Fig. 2 is an end elevation of the machine, illustrated as applied to a pulley rim. Fig. 3 is a side elevation of 30 the machine, looking toward the abrasive wheel. Fig. 4 is a detached view, partly in section and partly in elevation, of the abrasive wheel and the holder therefor.

The reference numeral 5 designates a 35 shaft to which a pulley 6 which is to be faced is keyed, said shaft being journaled in standards, such as 7. The shaft 5 is rotated by power devices as, for example, a belt 8 passing about a driven pulley 9 upon the 40 shaft.

10 represents a platform which may be a part of the support for the shaft standards or of framework immovable relatively thereto.

45 According to my invention, I provide a casting or bed plate 11 which is rigidly secured to the platform 10 and, as shown in Fig. 2, is provided with a longitudinal tongue 12 of an approximately dove-tail shape in cross-section.

Slidably mounted upon the bed-plate 11 is a carriage 13 having in its underside a dove-tail groove 14 to receive the tongue 12 of the bed-plate.

Depending from the carriage is an apertured projection 15 which is interiorly

screw-threaded to engage a feed-screw 16 which is journaled in a lug 17 of the bed-plate and is manually actuated, preferably, by a crank handle 18. Said carriage is provided with a transversely arranged dove-tail groove 19 to accommodate a correspondingly-shaped tongue 20 formed on the underside of a block 21. This block has in its tongue 20 a screw-threaded hole, 20¹, for engagement with an adjustment screw 22 having a wheel-handle 23 and extends through a strap 24 secured to the carriage to afford transverse feeding movements to the block with reference to said carriage.

25 represents a tool post provided with a head 25¹ at its lower end adapted to enter a groove 26 provided in the block. The tool post, like those commonly used with lathes, is formed with a slot 27. A set screw 28 extends into said slot for exercising a downward thrust upon the tool to cause a washer 30 therebelow to coöperate with the post head 25¹ to clamp the post to the block flanges 21¹. In this instance, two jaw members 29 and 29¹ are utilized in the post slot and are formed in their opposing faces with grooves in which seats the shank 31 of the holder of the abrasive wheel 32. As shown, said holder is bifurcated at its forward end 35 to furnish parallel branches 33 and 33¹. These branches are bored to receive a pin or shaft 34 upon which is journaled a sleeve 35. Said sleeve is formed at one end with a head 35¹ against which the abrasive wheel 32 is rigidly held by means of nuts 37 and 37¹ engaging screw threads provided on the sleeve.

38 and 38¹ represent nuts also engaging such screw-threads and are regulated to take up any end wear and have one of them bear against the holder branch 33¹.

39 and 39¹ represent annular thrust plates interposed between the sleeve-head 35¹ and the holder branch 33 and are desirably made 100 so that the alternate plates are of different metal as, for example, if the sleeve is constructed of brass, the plate 39 may be of steel and the other one 39¹ of brass.

34¹ represents a nut engaging screw 105 threads at an end of the pin 34 and acts with the bolt-head 34² to maintain the bolt against axial displacement. The pin is provided with a duct 40 for a lubricant to flow from a grease cup 41 at one end of the pin to the 110 bearing of the sleeve 35.

The operation of the invention so far de-

scribed may be explained as follows: The shank 31 of the holder for the abrasive wheel 32 is placed between the jaws 29 and 29¹ within the slot of the tool post. The holder is then turned about the axis of said shank to have the grinder wheel at an angle, say of about thirty-five degrees, from a vertical plane as indicated in Fig. 3. The set-screw 28 is then screwed down to raise the tool post and effect the clamping of the post to the block and the binding of the shank 31 of said holder between said jaws. The block 21 is then set forward by means of the regulating screw 22 so that the periphery of the grinding wheel will be tangent to the circumferential surface to which the pulley 6 is to be faced; whereupon the operator, by means of crank-handle 18, actuates the feed-screw 16 to move the carriage so as to carry the abrasive wheel transversely of the pulley 6 to accomplish a grinding effect thereupon. In such transverse travel of the abrasive wheel across the face of the pulley 6, and by reason of the inclination of the axis of the former, the same is rotated at a greater peripheral speed than the rim of wheel 6 and in consequence acts to grind the latter.

The invention is of simple construction, not easily deranged, and may be used to grind a wheel or pulley without removing it from its shaft.

What I claim is:

1. In a machine for grinding a pulley face, the combination of a rotary abrasive-wheel, a holder therefor, a carrier for said holder, means to afford movements to said carrier in directions parallel and rectangular to the axis of the pulley to be ground, and means for adjustably securing said holder to the carrier in selected rotary positions with respect to an axis extending diametrically through said wheel; whereby the rotation of said pulley effects the rotation of the abrasive wheel at a peripheral speed greater than that of the pulley.

2. In a machine for grinding a pulley face, the combination with a pulley, and

means to rotate the same, of a carriage movable parallel to the axis of said pulley, a block connected to said carriage and movable rectangular to the axis of the pulley, a tool post carried by said block, an abrasive wheel, a holder therefor, and means provided in said tool-post for supporting said holder in predetermined rotary positions to present said abrasive wheel in positions so that the latter will be rotated through the instrumentality of the pulley at a peripheral speed different from the peripheral speed of the latter to thereby cause the face of the pulley to be ground by the abrasive wheel when the latter is moved transversely thereof.

3. In a machine for grinding the face of a pulley, an abrasive wheel, a holder supporting said wheel for rotative movements on the wheel axis, means for positioning said wheel to have its axis inclined with respect to the axis of the pulley, and means whereby the wheel is adapted to be fed toward and parallel with the axis of the pulley and without varying the inclination of the wheel axis with respect to the pulley.

4. In a machine for grinding a pulley face, a bed-plate, adapted to be secured in fixed relation with respect to the axis of a pulley to be ground, a carriage mounted for travel on said bed-plate, means for propelling the carriage on said bed-plate, an abrasive-wheel, a shaft therefor, a holder for said shaft, means for securing said holder to the carriage whereby the shaft is rotated about an axis intermediate its ends to present the wheel in skew relations to the pulley so as to be rotated by frictional contact with said pulley and be driven by the latter so as to grind the pulley-face when the carriage is caused to travel through the agency of the propelling means.

Signed at Seattle, Washington, this 27th day of February, 1915.

WALTER C. BARNHART.
